UNITED STATES PATENT OFFICE.

THOMAS WOODS, OF SYRACUSE, NEW YORK.

VENDING-MACHINE.

1,105,477.

Specification of Letters Patent. Patented July 28, 1914.

Application filed May 27, 1912. Serial No. 700,001.

To all whom it may concern:

Be it known that I, THOMAS Woods, a citizen of the United States, residing at Syracuse, in the county of Onondaga and

5 State of New York, have invented certain new and useful Improvements in Vending-Machines, of which the following is a specification.

This invention relates to improvements in 10 vending machines, and the invention relates particularly to a coin controlled device adapted for vending chewing-gum, confections, and the like.

The object of the invention is to provide a 15 rotary vending machine which is novel, simple and positive, wherein the construction and arrangement of the parts are such that a large variety of goods such as candy, gum and other confections are carried by the device, and are capable of being automatically dispensed to the purchaser upon the insertion of coins of suitable denomination and size.

A further object is to provide novel coin 25 controlling parts, associated with a simple vending mechanism, which render the whole device effective, positive and quick acting, as well as, incapable of being tampered with.

The features and parts of the invention 30 will be understood from the detailed description which follows, and by reference to the accompanying drawings which form a part of the specification, and in which—

Figure 1 is a top plan view taken on line 35 1—1 of Fig. 2; showing the complete device with the shield removed. Fig. 2 is a central vertical cross section substantially on line 2—2 of Fig. 1. Fig. 3 is a horizontal section on line 3—3 of Fig. 2. Fig. 4 is a front side 40 elevation of the complete machine. Fig. 5 is an enlarged detail view; showing the coin controlling and vending mechanisms in the idle, and also in the operated position. Fig. 6 is an enlarged detail view of the coin carrying plate. Fig. 7 is a top plan view of the 45 coin gun; showing the working parts in full rest position. Fig. 8 is a side elevation of the same. Fig. 9 is a longitudinal section substantially on line 9—9 of Fig. 7; showing 50 the coin actuated parts in the second rest position. Fig. 10 is a similar view; showing the coin controlling parts when they are operated by a coin. Fig. 11 is a similar sectional view; showing the same parts after 55 operation. Fig. 12 is a detail elevational view of the lever which operates the ejector.

Fig. 13 is a sectional view on line 13—13 of Fig. 7; showing the pawl in position for preventing the repetition of the vending operation.

In the drawings, 2 represents a hollow casing or base which may be supported by any suitable means, or by a pedestal which is illustrated in part at 3. The top of the casing 2 has a circular opening 4 for the 60 insertion and operation of the vending parts.

5 represents a central rotatable shaft or rod which is disposed vertically and concentrically in the casing 2, and is pivoted at 6 near the bottom of the casing, the said shaft 65 being supported in vertical position by a bracket 7 in which it has a suitable bearing, the bracket being cast with or supported by the bottom of the casing in any suitable manner. The shaft 5 is rotatable in opposite directions by means of a pair of gears 8 and 9. The gear 8 is made rigid on the said shaft, while the gear 9 is mounted upon a horizontal shaft 10 which has bearings in lugs 11 which rise from the bottom of the 70 casing. The outer end of shaft 10 pierces the wall of the casing 2 and is fitted with a hand-wheel or knob 12, by means of which 75 the two shafts are rotated.

13 represents a circular bell-shaped part, 80 which is arranged concentric to the shaft 5 and rigidly secured thereto for operation with said shaft. The part 13 is disposed above the bracket 7, and slightly below the 85 top of the casing 2.

14 represents a number of radial slots, 90 which occur at regular intervals in the circumference of the part 13 just below its plain top.

15 and 16 represent elongated magazines 95 or chutes in which are disposed the candy, chewing-gum or other confections which the machine dispenses. The said magazines are preferably of different sizes or caliber 15 representing the larger ones which are preferably loaded with candy, as 15', and 16 representing the smaller ones which carry chewing-gum, or like smaller packages, as 16'. In the present device there are ten of the magazines 15 and 16, which provide for a 100 large variety of goods, and these are preferably arranged in a circle surrounding the main shaft 5. The lower ends of the magazines 15 and 16 rest upon an annular ledge 17 of the support or part 13, to which they 105 are detachably secured by means of dowels 18 carried by the magazines and which 110

pierce the said ledge. The upper ends of the magazines are held in place by catches 19 which are disposed on the under side of a disk-like cap or head 20 which is mounted 5 rigidly upon the upper end of the shaft 5 and held in place by a nut 20'. The magazines 15 and 16 all rotate with the shaft 5 and the support 13 and each of these parts may be brought to the vending position indicated by the arrow in Fig. 4, by the manipulation of the hand-wheel 12.

21 represents a weight which is placed upon the packages 15' and 16' in each of the magazines for holding the same under a 15 slight compression. The bottom ends of the magazines 15 and 16 are preferably open and free, and the lowermost packages of the gum and candy rest directly upon the ledge 17 of the part 13. The outer or front face 20 of each magazine is cut away so as to permit the free passage of the lowermost package of candy or gum, when the vending operation takes place.

22 represents a spring which is secured to 25 the face of each magazine, the said spring depending across the opening in the face of the magazine in position to prevent the accidental escape of the lowermost package. The springs 22 are intended to yield readily 30 when the ejector forces the packages through the opening in the face of the magazine. The magazines 15 and 16 are inclosed by a cylindrical cap or cover 23 which rests upon the top of the casing 2, to which it may be 35 secured by any suitable means.

The vending mechanism consists of the following parts: 24 represents a horizontally arranged ejector, which is disposed between the part 13 and the bracket 7, and is adapted 40 to reciprocate through the slots 14 of the part 13, for dispensing or ejecting the lowermost packages as the magazines are successively brought to the vending position opposite the arrow and the ejector. The 45 ejector 24 has a slot 25 through which the shaft 5 passes, and which acts as a guide for the ejector and when at rest it is disposed entirely beneath the top of the part 13 and clear of the slots 14 (see Fig. 3), and when 50 in this position the parts 5, 13, 15 and 16 may be freely rotated in either direction without interference by the ejector.

26 represents an L-shaped lever which is mounted upon a similar bracket 27 which is 55 secured to the support 7 beneath the ejector 24. The free end of the upright arm of the lever 26 is disposed in a slot 28 of the ejector 24, while the horizontal arm of the said lever is pivoted to the bracket 27 by a screw 60 29. The rotary movement of the lever 26 upon its pivot effects the reciprocation of the ejector 24, as indicated by the full and dotted lines in Figs. 3 and 5.

When the magazines 15 and 16 are rotated to the vending position, as described,

these and all of the other rotary parts are held in the proper position by a rocking lever 30 which is pivoted near one side of the casing 2, the said lever being yieldingly held against the inner lower edge of the part 13 by the tension of a spring 31. In order to render the lever 30 effective for holding a magazine in the vending position, the lower portion of the part 13 is serrated, as shown at 32 in Fig. 3, wherein the said lever 75 is shown in two positions, one for holding the rotary parts in place, and the other shows how the said lever yields under the tension of its spring 31 when the part 13 is rotated by the hand-wheel 12 and gears 8 and 9.

The vending mechanism consisting of the ejector 24 and the rocking lever 26 are operated and governed entirely by a coin controlled mechanism which will now be described:

33 represents generally what will be described as a coin-gun which is supported by a door 34 which closes an opening in the front of the base 2, the said door being held in closed position by a suitable lock which is controlled by a key 36. The coin-gun comprises a metal frame or part 37 which has a deep channel or groove 37' in its upper side, and oppositely arranged flanges 38 for attaching the gun to the door 34, as well as for gaging or limiting the insertion of a portion of the gun through a suitable perforation in the said door.

39 represents an elongated plate or bar 100 which is slidable upon the bottom of the groove 37' of the frame, beneath a block 40 which is also fitted in the said groove and secured to the frame by screws 41. The space between the block 40 and the bottom 105 of the groove 37' is barely sufficient to allow the free sliding movement of the plate 39.

42 represents a circular perforation or hole formed in the plate 39 to receive a coin 42' by means of which the device is 110 operated.

43 represents a longitudinal groove in the under side of the block 40 in which is pivoted a rocking dog or lever 44 by a pin 45, the forward end of the said dog being normally depressed by a spring 46. The forward end of the dog 44 is provided with downwardly facing teeth 47 and 48 which are adapted to engage the plain upper surface of the plate 39 when the said plate is 120 in the full release position shown in Figs. 5, 7 and 8, and when in the latter position the rear end of said dog which is formed into a downwardly projecting tooth or lug 49, is positioned in a slot 50 of the plate 125 39. When the plate 39 is in the last named position the said lug bears against the rear end of said slot and prevents the further outward movement of the said plate. When the plate 39 is pushed inwardly to its second 130

position, shown in Fig. 9, the tooth 47 of the dog 44 drops into the circular opening 42 which receives the coin for operating the vender, and at the same time the tooth 48 drops into a small slot 52 in the plate 39 just rearwardly of the hole 42, and thereby steps the further inward movement of the plate 39. This latter feature is provided for preventing the operation of the coin plate 39 for actuating the vending or dispensing mechanism when no coin is inserted in the hole 42.

53 represents a stud or pin which is loosely mounted in a corresponding socket 15 formed in the frame 37, the said pin adapted to be projected above the bottom of the groove 37' in the path of the plate 39 by a spring 54 when the perforation 42 is empty, and at such times the said pin engages the 20 forward or outer side of the said perforation for coöperating with the dog 44, for preventing the full inward movement of the coin plate when the latter is operated, as with a quick short jerk. Either the dog 25 44 or the pin 53, will effect the stopping of the inward movement of the coin plate 39, if the latter is operated slowly in the usual way. The outer end of the coin-plate 39 is bent upwardly at right-angles to provide 30 a push-lug or handle 39', by means of which the said plate is forced inwardly for operating the vending parts. To the inner end of the plate 39 is fitted an arm 55, which supports a pin 56, which operates the lever 26 in the direction for returning the ejector 24 to the rest position after each vending 35 operation.

57 represents a spring, one end of which is secured to the door 34, the other end connecting with the pin 56, the said spring exerting its tension for holding the coin-plate 39 in its outward position, shown in Figs. 1, 3, 4, 5, 7 and 8, in readiness to receive a coin which may be inserted in the hole 42.

45 58 represents a perforation formed in the bottom of the groove 37' of the gun concentric to the hole 42, the hole 58 being of smaller diameter, so that when a coin is inserted in the hole 42 it will rest and slide 53 upon the upper surface of the bottom of the groove 37'. The hole 58 is provided for permitting the operator to adjust the coin, or to remove it entirely after it has been placed in the hole 42. The arrangement of 55 the coin-gun is such that the reciprocating plate or bar 39 may be shifted and set or held in three different positions, as best seen in Figs. 8, 9 and 11, in which the first is the full release or rest position, and when 60 in said position a coin may be inserted in the hole 42 for effecting the dispensing of the goods. The second position is shown in Fig. 9, to which the reciprocating plate 39 may be operated without the insertion 65 of a coin, and without in anywise affecting

the vending parts. The dotted lines in Fig. 5 and the full lines in Fig. 11, show the coin carrier 39 operated to its third position, for ejecting the goods, which operation may only be effected when the coin 42' is placed 70 in the hole 42 (see also Fig. 10). When the part 39 is operated to the last position, a shoulder 59 of the arm 55 engages the horizontal arm of the lever 26, and swings it around from the position shown in full 75 lines, to that shown in dotted lines in Fig. 5, which effects the vending throw or movement of the ejector 24, which will then slide outwardly through one of the slots 14 for displacing and forcing the lowermost pack- 80 age of candy 15' out of the magazine 15, as is also shown in Fig. 5. When a package of the goods is discharged, as explained, it gravitates into a chute 60 which extends through the door 34, and lands in a pocket 60'. 85

61 represents a V-shaped pawl, which is pivoted in a slot 62 of the block 40 by a pin 63, and 64 represents a spring which rides upon the top of the said pawl, and gives it suitable tension for performing its work, the 90 said spring being held in place by a screw 65. 66 represents a series of ratchet teeth or notches formed in the upper face of the coin plate 39, in the path of the pawl 61. The object of the pawl and ratchet teeth is 95 to provide positive means for preventing the repeating of the vending operation of the plate 39 without the insertion of a second coin. When the plate 39 is operated by the insertion of a coin as illustrated in Figs. 10 and 11, without the employment of the pawl 61 the operator might withdraw the coin 100 plate 39 a short distance (see Fig. 13), and then shove the said plate inwardly again with a quick jerk, and thus repeat the vending operation. When the coin plate 39 is operated to the full extent as shown in Fig. 11, the point of the pawl 61 is positioned in a small slot 67 of the plate 39. When however, the plate 39 is withdrawn a slight distance, as described, the point of the pawl leaves the slot 67 and engages the ratchet teeth 66, in the manner shown in Fig. 13, which, owing to the inclination of the pawl will prevent the plate 39 from being again 110 operated inwardly, or to the right, until it has been allowed to return to its full released position by the power of the spring 57, as shown in Figs. 1, 2, 4, 5, 7 and 8. If the operator places a coin in the hole 42 and shoves the plate 39 inwardly to the extent shown in Fig. 10, he cannot withdraw the said plate for recovering the coin, because the point of the pawl 61 which is positioned 120 in a slot 68 of the plate 39, while the said plate is in the released position, moves out of the said slot and engages the ratchet teeth 66, in the manner shown in Fig. 10. The pawl will be held in the inclined position shown in the latter figure, by the power of 130

the spring 64 and will prevent the return movement of the plate 39. By this arrangement after the coin is inserted and the device is partially operated the operator must 5 complete the inward throw or movement of the plate 39 so as to allow the dog 44 to release the coin, as shown in Fig. 11, after which the plate 39 will be returned to the release position by the spring 57. The coin 10 42' after being discharged by the dog 44 falls into an inclined chute or spout 69 which is secured to the inner side of the door 34.

The construction and arrangement of the casing 2, the shaft 5, the support 13 and the 15 magazines 15 and 16, are unimportant, and may follow any of the old or suitable plans. The essentially novel features and parts of the invention consist principally of the coin-gum 33, the lever 26, the ejector 24 and 20 related parts, and their application to and operation of the main vending machine.

The foregoing describes, and the drawings show, the construction, arrangement and operation of my improvement, which 25 obviously may be changed or modified within the scope of the appended claim, without departing from the spirit of the invention.

Having thus described my invention, what I claim as new, and desire to secure by Letters Patent, is—

In a vending machine, a coin-gum comprising a hollow frame, a reciprocating coin-plate slideable in said frame having a socket for receiving a coin, and having an elongated slot spaced from said socket, a rocking dog carried by said frame above said plate, one end of said dog normally positioned in said slot when said plate is in the coin-receiving position for limiting the release-movement of said plate, the opposite end of said dog having a tooth adapted to be forced downwardly into said socket when empty for preventing the full vending-movement of said plate, a spring for forcing and holding said tooth in said socket, and means for preventing the repetition of the vending-movement of said plate unless a second coin is inserted in said plate.

In testimony whereof I affix my signature in presence of two witnesses.

THOMAS WOODS.
